(57) **CLAIM**

The ornamental design for a sprayer, as shown.

DESCRIPTION

FIG. 1 is a side elevational view of one side of a sprayer showing our new design;

FIG. 2 is a side elevational view of the other side;

FIG. 3 is a top plan view thereof;

FIG. 4 is a bottom plan view thereof;

FIG. 5 is a front elevational view thereof;

FIG. 6 is a rear elevational view thereof.

FIG. 7 is a front perspective view thereof, shown at a reduced scale; and,

FIG. 8 is rear perspective view thereof.

The broken lines shown in the accompanying drawings are for illustrative purposes only and do not form part of the claimed design.
